UNITED STATES PATENT OFFICE.

CINCO S. ODA, OF BOSTON, MASSACHUSETTS, ASSIGNOR OF ONE-HALF TO PETER N. FISHER, OF BOSTON, MASSACHUSETTS.

BELT BUCKLE.

1,417,855.

Specification of Letters Patent. Patented May 30, 1922.

Application filed March 19, 1921. Serial No. 453,597.

To all whom it may concern:

Be it known that I, CINCO S. ODA, a citizen of Japan, residing at Boston, in the county of Suffolk and State of Massachusetts, have invented certain new and useful Improvements in Belt Buckles, of which the following is a specification.

This invention relates to improvements in belts, the principal object of the invention being to provide means for preventing the buckle and front part of the belt from moving upwardly above the top of the trousers.

A further object of the invention is to provide a button carrying member for engaging the belt buckle and provided with clamping means so that it can be detachably secured to the trousers so that it can be easily and quickly removed from one 20 pair of trousers and placed on another belt.

A further object of the invention is to provide the buckle on the belt with means for detachably engaging the button for holding said belt in a certain position 25 against upward movement.

This invention also consists in certain other features of construction and in the combination and arrangement of the several parts, to be hereinafter fully described, 30 illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a fragmentary front view showing the invention in use.

40 Figure 2 is a section on line 2—2 of Figure 1.

Figure 3 is a view looking towards the rear of the buckle.

Figures 4 and 5 are detail views of the 45 button carrying clamp.

Figure 6 is a front view of a portion of a pair of trousers with the button carrying clamp in operative position thereon.

In these views 1 indicates the belt and 50 2 the buckle thereof. This buckle is provided with a transverse bridge-piece 3 at its rear which is provided with a slot 4 which begins at a point about midway the

ends of the bridge-piece and extends upwardly and passes through the top of the 55 buckle. The upper end of the slot is widened, as shown at 5. Disposed between the bridge piece 3 and the front part of the buckle is a guard 3' which is provided by pressing a portion of the bridge piece 60 inwardly when forming the aforesaid slot 4. This guard prevents contact between the belt and the top of the button.

A clamp 6 carrying a button 7 is adapted to be attached to the top of the trousers A 65 with the button 7 engaging the slot 4 in the bridge-piece so as to prevent the buckle and belt from slipping upwardly off the trousers. The button engages the lower closed end of the slot and thus securely 70 holds the buckle in position upon the trousers. The enlarged end of the slot facilitates the entrance of the button thereinto. The clamp may be of the well known type, as shown in the drawing, consisting of the 75 U-shaped member 8 with the U-shaped spring 9 therein, the spring being contracted by the lever 10. Thus the clamp can be made to grip a portion of the trousers by forcing the spring inwardly by the 80 lever.

The clamp with the button thereon is placed adjacent the upper edge of the trousers, as shown in the drawing and the belt buckle is brought to a position where the 85 button 7 can engage the slot 4 in the bridge-piece, so that when the belt is buckled around the waist the buckle and belt will be prevented from riding upwardly off the trousers. 90

By my invention the use of straps at the front of the trousers is rendered unnecessary, such straps being undesirable for if they are placed too far apart the belt buckle will work upwardly or if placed close together to prevent this it is very difficult to adjust the belt. 95

It is thought from the foregoing description that the advantages and novel features of my invention will be readily apparent. 100

I desire it to be understood that I may make changes in the construction and in the combination and arrangement of the several parts, provided that such changes fall within the scope of the appended 105 claim.

What I claim is:—

In combination with a belt, a buckle thereon having a transversely arranged bridge piece at its rear, spaced from its front part, said bridge piece having a vertically arranged slot in its upper part having an enlarged upper end which extends

into the upper side of the buckle, and a stud adapted to be connected with the trousers for engaging the slot for preventing the buckle and belt from moving upwardly upon the trousers. 10

In testimony whereof I affix my signature.

CINCO S. ODA.
